UNITED STATES PATENT OFFICE

IRWIN W. MILLARD, OF CHICAGO, ILLINOIS, ASSIGNOR TO INDUSTRIAL GLOVES CORPORATION, OF CHICAGO, ILLINOIS, A CORPORATION OF DELAWARE

ARMORED FOOT AND ANKLE PROTECTOR

Application filed April 27, 1929. Serial No. 358,471.

The invention relates particularly to armored or reinforced foot coverings and has for its general aim the provision of a new and improved protective covering for the 5 foot which is especially reinforced to afford protection to certain portions thereof.

In certain industrial plants, such as steel rolling mills, serious and often permanent injuries are frequently caused by accidents to 10 the feet of the workmen. For example, in a steel rolling mill workmen are employed in handling heavy sheets of metal which may move near the floor and which have jagged or sharp edges. Accidental striking of the 15 foot against these edges may, and often does, sever or otherwise seriously injure certain important tendons in the foot, such as those across the instep or the Achilles tendon at the rear of the foot and ankle. Generally 20 such injuries result in permanent disability of the injured workman.

A more specific object of the invention, therefore, is to devise an article of this character which is strongly armored or reinforced 25 to afford protection across the instep of the foot and to the Achilles tendon.

Other objects and advantages will be apparent in the following description and from the accompanying drawing, in which:

30 Figure 1 is a side elevation of a foot covering embodying the features of this invention.

Fig. 2 is a vertical central section of the covering.

Fig. 3 is a transverse section thereof.

35 Although the invention is susceptible of various modifications and alternative constructions, I have shown and herein described in detail the preferred embodiment but it is to be understood that I do not thereby intend 40 to limit the invention to the specific form disclosed but intend to cover all modifications and alternative constructions falling within the spirit and scope of the invention as expressed in the appended claims.

45 Generally, the invention comprises a foot covering of suitable material, such as leather or the like, which may be readily attached or detached from its position about the wearer's foot and which embodies therein one or 50 more steel strips particularly arranged to

overlie and protect the various portions of the foot most likely to be seriously injured by accident.

More particularly, the covering is shown as being generally in the form of a spat and 55 may be formed in any suitable manner. In the present instance three pieces of a suitable material, such as leather, are cut on appropriate patterns to provide an inner section 6, a front outer section 7, and a rear outer section 60 8. The front outer section 7 is secured to the inner section 6 along one side edge thereof, as by means of the steel staples 9, these blanks being designed to form a flare portion 10 on the spat for overlying and protecting the 65 instep of the foot.

The outer rear section 8 is secured to the opposite side of the inner section 6 in the same manner, this portion of the spat being formed to accommodate the heel of the foot. 70 Complementary snap fasteners 11, extending between the adjacent edges of the front and rear outer sections 7 and 8, provide simple means for adjustably securing the spat about the foot. The well known arrangement of a 75 strap 12 which passes beneath the instep of the foot, and a buckle 13 for engaging the strap may also be provided to hold the spat snugly down on the foot.

80 Preferably the height of the spat when worn is such that the upper edge thereof extends well above the wearer's ankle thus covering the whole of the lower and most exposed portions of the leg and the important tendons located therein. The entire surface 85 of the spat is preferably reinforced by a plurality of steel staples 14, which type of reinforcement strengthens but does not materially affect the flexibility of the article.

89 The particular means for protecting those portions of the wearer's foot more likely to be injured are illustrated, in this embodiment, as being arranged to overlie and protect the tendons across the instep of the foot and the Achilles tendon at the rear of the foot. To 95 this end armoring stays or strips 15 and 16, of somewhat flexible, tempered steel, extend from top to bottom of the spat along the front and rear portions respectively. Said stays are secured in position in any suitable 100

manner, as by providing pockets therefor by overlapping portions of the sections 6, 7 and 8 as shown in Fig. 3, when these portions are sewed together. The front stay 15 is preferably slightly arcuate to conform to the contour of the instep.

In consequence of this construction, it will be apparent that the armoring stays will be supported in such position upon a wearer's foot, that a sharp object coming forcibly into contact therewith will meet with a positive resistance which is of ample strength to prevent severing of the underlying tendons. Moreover, an article of this character is simple in construction, will not interfere with the movements of the wearer, and may be manufactured at a low cost.

I claim as my invention:

1. A reinforced protecting means for the lower portion of a leg comprising, in combination, a flexible covering adapted to encircle the exposed parts of a wearer's foot and ankle, means for securing said covering in place, and reinforcing means for strengthening said covering including small metallic members disposed in closely spaced relation about the surface of said covering, and a pair of metal stays secured to said covering to extend from top to bottom thereof, said stays being positioned one on the front of said covering to overlie the wearer's instep, and the other at the rear of said covering to overlie the Achilles tendon.

2. A foot and ankle protecting means comprising, in combination, a covering member shaped to overlie the exposed portions of a wearer's foot and ankle, means for strengthening said covering including small metallic members disposed in closely spaced relation about the surface of said covering, and means for armoring said member comprising strips of material of relatively great strength carried by said member to overlie and protect certain parts of the foot and ankle.

45 In testimony whereof, I have hereunto affixed my signature.

IRWIN W. MILLARD.
